UNITED STATES PATENT OFFICE.

DAVID O. PAIGE, OF DETROIT, MICHIGAN.

SAFE OR VAULT.

SPECIFICATION forming part of Letters Patent No. 425,451, dated April 15, 1890.

Application filed September 11, 1889. Serial No. 323,662. (No model.)

To all whom it may concern:

Be it known that I, DAVID O. PAIGE, a citizen of the United States, residing at Detroit, county of Wayne, State of Michigan, have 5 invented a certain new and useful Improvement in Safes or Vaults; and I declare the following to be a full, clear, and exact description of the invention, such as will enable others skilled in the art to which it pertains 10 to make and use the same, reference being had to the accompanying drawings, which form a part of this specification.

In the drawings, Figure 1 is a view in section of a part of a safe-door embodying my 15 invention. Fig. 2 is an enlarged view illustrating the spindles of the combination knob or handle. Fig. 3 is a variation. Figs. 4 and 5 are separate views of the washers.

Heretofore in the construction of doors of 20 safes and vaults in which the bolt-work or combination-tumblers have been operated from the outside by spindles projecting through the door an element of insecurity has arisen, as follows: The said spindles must 25 of necessity be fitted sufficiently loose so as to turn easily without binding and yet be tight enough to prevent the introduction of powder or other explosive into the safe about the spindle. To this end it has been customary 30 to make them in conical or double conical form and to grind the spindle and its orifice to a close fit. This effectually prevented the introduction of powder; but it has been found that nitro-glycerine could be introduced 35 around even such a close-fitting spindle. To accomplish this the operator closes all orifices except this at the spindle and one other. At this second point he then applies an exhaust-pump, by which he produces a more or less 40 perfect vacuum within the safe. This can be relieved only by the small amount of air that can enter about the spindle. He then feeds nitro-glycerine about the spindle, and the latter is thus sucked into the safe. When enough 45 has been inserted, it is exploded and results in forcing the safe-door from its seat and opens the safe. So, again, even though the nitro-glycerine might not be fed fully into the 50 safe, it might be fed in around the orifice of the spindle, and by exploding it serve to disrupt the plates or break and blow out the

spindle or enlarge the opening through which glycerine could be readily passed.

It is the purpose of my invention to provide means whereby the safe or vault is made 55 secure against the admission of nitro-glycerine or other explosive either about the spindles or around the edges of the door. To this end A represents a portion of a safe, and A' its door.

B is the spindle of the combination-lock, 60 and C the spindle of the door-handle, by which the train-bolts are thrown to lock or unlock the door.

D represents the various plates composing 65 the safe-door. These spindles may be of any usual form. Those shown in the drawings are in double conical form.

E' represent washers, of leather, rubber, or other suitable material, grooved out at e, so that their thin edges shall constitute valves. 70 The cavities e present, respectively, toward the interior and exterior, as shown. I place them as near as convenient to the inner and outer surfaces of the safe-door.

E² represents metallic or other washers, 75 which may or may not be employed, dependent on whether the leather washers E' do or do not fill the cavities made for them. I then preferably soak the leather washers in oil or paraffine or equivalent substance to 80 soften the same and keep them soft.

Now, suppose an operator has closed the cracks, as explained, except at one of the spindles, and has applied his exhaust-pump, as described. He proceeds to exhaust the air 85 from the interior, creating an inward suction at the spindle. It is apparent that the valve-edges e of the outer leather washer E will at once close tight upon the spindle and valve-cavity and prevent any ingress of air about 90 the spindle. It will be impossible, therefore, by this means to introduce nitro-glycerine at this point. It prevents it from even starting in about the spindle. It is apparent that it cannot be introduced even through the first 95 plate, and cannot, therefore, be worked into the cavities between the plates. Again, suppose he should attempt to exhaust through the space about one spindle while he endeavored to feed the glycerine about the other 100 spindle or into some other orifice. He would be at once thwarted, for at that spindle where

his exhaust was applied the valve of the inner washer E' would close around the spindle, preventing egress of air, while the valve e of the washer E on the other spindle would close 5 and prevent ingress of glycerine at that point. Of course the form of the valve may be varied, and in some instances it might be in the form of a plain elastic washer adapted to hug the spindle, as shown at E³ in Fig. 3. Thus it 10 might be of felt, asbestos, or any other elastic substance, and might be saturated with oil or other filling. So, also, in order to prevent the operator from damming up the edges of the door and leaving two small openings 15 through which the air may be exhausted and the glycerine admitted, I preferably provide a lining or packing a, of felt, leather, or analogous substance, entirely around the joint between the door and adjacent wall. Thus 20 when the door is closed this lining, which I prefer to soak with some suitable filling, completely closes the joint and prevents either the exhausting of the air or the admittance of the explosive.

25 What I claim is—

1. The combination, with the spindle of a

safe or vault door, of a valve or valves surrounding the spindle and adapted to prevent the passage of air or liquid along the spindle, substantially as and for the purposes de- 30 scribed.

2. The combination, with a safe-door and its spindle, of two valves surrounding the spindle, one adjacent to each wall, each adapted to prevent ingress of air along the 35 spindle from its respective end of the spindle, substantially as described.

3. The combination, with the safe-door and spindle, of a valve of leather hollowed out at e, as shown, and substantially as described. 40

4. The combination, with a safe-door, its spindle surrounded by one or more valves and the adjacent safe-wall, of a lining of felt, leather, or analogous material filling the joint between the door and the wall, substan- 45 tially as described.

In testimony whereof I sign this specification in the presence of two witnesses.

DAVID O. PAIGE.
